UNITED STATES PATENT OFFICE.

RICHARD H. L. TALCOTT, OF BROOKLINE, MASSACHUSETTS.

SOAP-PULVERIZING MACHINE.

SPECIFICATION forming part of Letters Patent No. 784,767, dated March 14, 1905.

Application filed August 27, 1901. Renewed August 15, 1904. Serial No. 220,708.

To all whom it may concern:

Be it known that I, RICHARD H. L. TALCOTT, a citizen of the United States of America, and a resident of Brookline, in the county of Norfolk and State of Massachusetts, have invented certain new and useful Improvements in Soap-Pulverizing Machines, of which the following is a full, clear, and exact description.

This invention relates to machine for pulverizing soap or making "soap-flour," as the product is sometimes termed.

The object of the invention is to provide an improved and simplified machine for the working up of a plurality of bars of soap into a comminuted condition, the soap-flour as thus produced being adaptable especially for the washing of fine woolen fabrics and laces.

The machine as contemplated under this invention comprises in the composition thereof a suitable frame or supporting structure, a rotatable and preferably power-driven gauze or screen covered or otherwise foraminous or suitable abrading-cylinder for exerting a comminuting or pulverizing action upon the bars of soap, a support adjacent the cylinder for the bars of soap, means for the constraint and guidance of the soap-bars as they are gradually fed forwardly to remain subject to the abrasive and comminuting action of the cylinder, and a follower for exerting a proper degree of pressure against the soap bars to constantly maintain them in position to be ground away by the cylinder; and the invention, furthermore, comprises a receptacle for the reception of the soap-flour and a casing or cover for suitably inclosing the cylinder, whereby that proportion of the powdered soap which is carried more or less around with the cylinder and finally is thrown therefrom centrifugally may be restrained against being scattered, so that it will settle down into the receptacle for the flour.

The invention, furthermore, comprises in a machine for the purpose stated, characterized as above, means for insuring automatically the cessation of the impelling force against the follower at approximately the time when the bars are almost completely reduced, so that the follower will not itself be brought

against the cylinder to injuriously act thereon or to be injuriously acted upon thereby.

The invention also comprises details of constructions and particular combinations of parts, all substantially as hereinafter described, and pointed out in the claims.

Reference is to be had to the accompanying drawings, in which my present improved machine is fully and clearly illustrated, and in which—

Figure 1 is a side elevation, the inclosing casing for the cylinder being indicated as swung rearwardly open. Fig. 2 is a plan view of the machine with parts of the double screen-covering for the cylinder broken away to illustrate the construction of the screen-supporting part of the cylinder. Fig. 3 is an end elevation of Fig. 1. Fig. 4 is a partial vertical cross-sectional view of the machine with the screen-inclosing casing in its closed position.

Similar characters of reference indicate corresponding parts in all of the views.

In the drawings, A represents the frame and supporting structure of the machine, having suitable standards or uprights provided with the bearings *a* for the driving-shaft *B*, on which is mounted the abrading-cylinder *C* for the reduction of the soap bars *w*, and said shaft has thereon the driving-pulley *D*. The cylinder ranges horizontally and axially longitudinally of the machine and, as shown, has for the supporting structure thereof a plurality of disks *b b*, understood as centrally circularly apertured and fitted on the shaft and held in separation by the intermediate disks *c c* of smaller diameter.

Directly overlying the disks *b* is a screen *w* or analogous open-work structure, having interstices comparatively wide, the same being secured in any suitable manner, and on this suitably-continuous support is placed the overlying covering, which is most advantageously composed of comparatively fine wire-gauze *y* and is preferably made with the warp-wires—those which run longitudinally of the cylinder—formed with squared or otherwise sharp edges for increasing efficiency in the abrading action on the soap bars.

Located at the front of the cylinder is a shelf-like support or table E, on which the bars of soap rest and are horizontally slid or gradually fed thereover for endwise presentation against the abrading-periphery of the cylinder.

F represents a follower, here shown as consisting of a wooden bar resting on the soap-support, ranging longitudinally parallel with the cylinder-axis and adapted to bear against the outer end of the several bars of soap, which are shown as separated from each other and held not only in their separation, but also against rising by the rack-frame G, which has one end thereof hinged to an upright d, extending above the level of the soap-support, said rack-frame comprising, in addition to the longitudinal bars f, one or more, to rest against or to have positions adjacent the tops of the soap bars, the transverse bars g, between the several of which the soap bars are disposed. The follower, which is free for a horizontal transverse motion, has the soap-crowding pressure imparted thereto by the stress of the sheave-guided cord or cords h, one end of each of which is attached to the follower, while at its depending end is a suitably heavy weight i. The table and the rack-frame G may be regarded as a carrier or feed-receptacle and as a matter of expediency may be removable from the machine without interference with or interference by the follower, so that a removed carrier could be loaded while another was in use in the machine.

H represents a shelf onto which the weights may be lifted to rest, leaving the cords slack when the machine was not in use, so that the follower F may be drawn forwardly beyond the table E onto the portion of the framing j, to enable the removal of the table and rack to be loaded with bars or blocks of soap and the replacement thereof by another loaded carrier.

Hinged to the framing at the rear of the cylinder is a casing J for inclosing the cylinder when the machine is in operation and for preventing that proportion of the powdered soap which does not pass directly from the soap-bars, from which it is worked off into pulverized condition down into the receptacle M below the cylinder, but which is carried partially or completely around with the cylinder and finally centrifugally thrown therefrom, from being scattered. The aforesaid receptacle M beneath the cylinder may be drawn endwise of the machine outwardly sufficiently far to enable one to remove the soap-flour therefrom.

m m, Figs. 2 and 4, indicate rods for the support of grating o and plate n, the latter to prevent the remnants of soap at about the end of the soap-reducing operation from mingling with the soap-flour in the receptacle, while the grate facilitates the passage of

the flour into the receptacle, especially between the soap bars, whereat the soap-bar support E may be suitably apertured, and in order that the follower may not be crowded toward the cylinder in the soap-reducing operation at the final stage when only small segments of the soap-blocks remain a shelf or other limiting appliance, as indicated at N, is provided suitably below the weights i. The rest N, which is shown as being adjustable and having its position properly to intercept the descent of the weights in proper time, insures a termination of the stress by the follower toward or against the cylinder.

The purposes and capabilities of the devices and incidentally their manner of operation having been explained in conjunction with the specification of the parts and devices, further description of the operation and mode of utilization of the machine is deemed superfluous.

I may advantageously make the outer covering or the support therefor which is mounted on the disks, or both, sectional, so that in case portions thereof become broken or worn out they may be replaced readily and at small expense.

By the employment for the abrading-surface of the cylinder of the covering of gauze, having one set of the woven wires thereof arranged longitudinally of the cylinder and the other set at right angles thereto and in planes perpendicular to the axis of the cylinder, I am enabled to produce the flour of soap which as to the nature or formation of the particles is of great uniformity and of a character susceptible of becoming readily dissolved in use. This will be explained as follows: In the action of the cylinder against the soap bars the longitudinal wires of the gauze exert an action for producing thin shavings more or less curled and feathery, and the round running wires of the gauze operate to cut the shavings into even particles. Were a cylinder having a grating-surface employed, there would be a great diversity in the size of the particles, as well as a greater solidity of many of the particles, and the failure to derive a product as desirable and acceptable as that of this machine.

Having thus described my invention, what I claim, and desire to secure by Letters Patent, is—

1. In a machine for pulverizing a plurality of bars of soap, in combination, a rotary abrading-cylinder, an adjacent soap-bar support, a frame or rack having upper longitudinal bars to constrain the soap bars from rising, and having transverse bars to extend between and hold the soap bars separated, a follower resting on the support behind the soap bars, and means for imparting an impelling force to the follower.

2. In a machine for pulverizing a plurality

of bars of soap, in combination, a rotary abrading-cylinder, and an adjacent soap-bar support, a part hinge supported above the support and arranged to be swung to a position over the soap bars, and having separated members extending in lines at right angles to the axis of the cylinder, for disposition between and to hold separated the soap bars, a follower and means for imparting an impelling force thereto.

3. In a machine for pulverizing soap, in combination, a frame, a rotary cylinder mounted therein, a soap-bar support or table having a rack hinged to the soap-bar support, and having members to overlie the soap bars and members to constrain such bars in separation, the follower, and means for imparting an impelling force thereto.

4. In a machine for pulverizing soap, the combination with the frame, the soap-bar support, the follower, and means for imparting a crowding force to the follower, of the cylinder mounted in the frame and consisting of a journal-shaft, the disks *b*, the separating intermediate disks *c*, of smaller diameter, and an abrasive covering forming the peripheral surface of the cylinder.

5. In a machine for pulverizing soap, in combination, the frame *A* having the adjustable bar *N*, the shelf or support *L* and the shelf *H*, the rotary abrading-cylinder mounted

in an upper portion of the frame, the horizontal soap-support adjacent the cylinder, the rack or frame *G* comprising the longitudinal upper bars, *f*, and the depending transverse bars *g*, said frame being hinged to swing upwardly away from, and into approached relation to, the soap-support, the follower, the sheave-guided flexible connections attached thereto having the weights, the cylinder-in-closing casing *J* and the powdered soap-receptacle beneath the cylinder resting on said support *L* and adapted to be drawn therealong from under the cylinder, all arranged and combined for coöperative action, substantially 35 as described.

6. In a machine for pulverizing soap, in combination, the abrading-cylinder and an adjacent table-like soap-bar support, and means for constraining the bars of soap in 50 their parallel movements toward the cylinder, a follower for pressing the soap bars, a plate *o* to intercept soap remnants and the grating *n* outwardly beyond the plate, and the receptacle *M*, beneath the cylinder, substantially 55 as described.

Signed by me at Boston, Massachusetts, this 23d day of August, 1901.

RICHARD H. L. TALCOTT.
